UNITED STATES PATENT OFFICE

ARCHIBALD L. LEITCH, OF MARINE CITY, MICHIGAN

SHELL FOR WATER-HEATING COILS

Application filed December 14, 1927. Serial No. 240,003.

The present invention relates to a shell for the coil of water heaters and has for its principal object to arrange an inner shell within the coil housing adapted to form a trap for 5 the heat in order to retain the same in contact with the coil so as to obtain the greatest possible result from the heat provided for heating the coil whereby to improve the efficiency and promote economy in the use of devices of this 10 character.

A further object of the invention is to provide an attachment of this character which may be readily installed in operative position about the coil of water heaters of this character without necessitating any changes in the construction or operation thereof, and which at the same time is of a simple and practical construction, inexpensive to manufacture and otherwise well adapted for the purposes for 20 which the same is intended.

Other objects and advantages reside in the special construction and combination of the various elements comprising the invention, reference being had to the accompanying 25 drawings forming a part hereof, wherein:

Figure 1 is a vertical sectional view through the heater illustrating the construction of the inner shell therefor, and

Figure 2 is a transverse sectional view 30 therethrough.

Referring now to the drawing in detail, I have shown my invention adapted for use particularly with respect to water heaters wherein a spirally arranged water coil pipe 5 is disposed vertically within a housing 6, with its feed and discharge pipes 7 and 8 respectively extending laterally therefrom and beneath which may be arranged the heating element 9, which is in the form of a gas burner. 35 At the upper end of the housing 6 is arranged a stack 10 providing for the escape of the gas and heat generated in the housing through the use of the burner.

It is the usual practice in devices of this 45 character to permit the heat generated by the burner to pass directly upwardly through the coil 5 and allow the same to escape through the stack 10 and it is found that very little of the heat is retained within the housing for circulation about the coil.

In order to retain the heat about the coil so as to utilize a greater portion thereof in performing the heating function, I provide a shell 11 arranged within the housing having its wall disposed in spaced relation therefrom 55 and forming a substantial closure for the coil. The lower end of the shell is open providing for the free admission of the heat from the burner 9 and at spaced intervals about the lower edge of the shell I arrange brackets 12 60 by means of which the shell is secured to the wall of the housing.

The shell is formed of double walls arranged in spaced relation and comprising an inner wall 15 and outer wall 16 closed at their upper and lower ends whereby to form an air space between the walls of the shell as indicated at 17. A plurality of openings 18 are formed adjacent the upper portion of the inner wall and similar openings 19 are 70 formed adjacent the lower end of the outer wall 16. Inasmuch as the top of the shell is closed it will be apparent that the heat after passing upwardly through the coil will escape through the openings 18 and pass downwardly between the walls 15 and 16 and out through the opening 19 of the lower portion thereof, as indicated by the arrows, into the housing so that the same will be permitted 75 to escape through the stack.

One side of the housing 6 may be provided with a door 20 affording access for lighting and controlling the burner 9.

It will be apparent that by providing a shell of this character about the coil that a substantial portion of the heat will be retained therein and to which the coil is subjected. By preventing the immediate escape of the heat from the housing the heating of the coil will progress more rapidly and also enable a reduction in the amount of fuel consumed in order to supply the necessary heat to the coil.

It is obvious that the invention is susceptible of various changes and modifications, without departing from the spirit or scope of the invention or sacrificing any of its advantages, and I accordingly claim all such forms of the device to which I am entitled. 95 100

Having thus described my invention what I claim as new is:

In a heater of the class described comprising a housing having a heating element and a coil arranged therein in heating relation with respect to each other, said coil having its convolutions disposed in spaced relation and a shell arranged within the housing with their respective walls in spaced relation and with the walls of the shell spaced outwardly from the coil, said shell having its lower end open for receiving the hot gases from the heating element and closed at its upper end for preventing the escape of the said gases at the top thereof, said shell being formed with inner and outer spaced walls closed at their upper and lower ends and provided with openings communicating with the space therebetween, said openings in the inner walls of the shell being disposed at the upper portion thereof with the openings in the outer walls of the shell disposed at the lower portion thereof and communicating with the housing, whereby to provide a flue within the housing for directing the gases downwardly between the walls of the shell after passing from the coil into the housing.

In testimony whereof I affix my signature.

ARCHIBALD L. LEITCH.
